(57) **CLAIM**

The ornamental design for a ceiling attaching type air conditioner, as shown and described.

DESCRIPTION

FIG. 1 is a front view of a ceiling attaching type air conditioner showing my new design.

FIG. 2 is a rear view of the ceiling attaching type air conditioner of FIG. 1.

FIG. 3 is a left side view of the ceiling attaching type air conditioner of FIG. 1.

FIG. 4 is a right side view of the ceiling attaching type air conditioner of FIG. 1.

FIG. 5 is a top view of the ceiling attaching type air conditioner of FIG. 1.

FIG. 6 is a bottom view of the ceiling attaching type air conditioner of FIG. 1; and,

FIG. 7 is a perspective view of the ceiling attaching type air conditioner of FIG. 1.

The broken lines illustrating the radiation panel of the ceiling attaching type air conditioner form no part of the claimed design.
